UNITED STATES PATENT OFFICE.

WILLIAM NESS, JR., OF SPRING FORGE, PENNSYLVANIA.

DESIGN FOR A HARNESS-TUG.

SPECIFICATION forming part of Design No. 29,702, dated November 22, 1898.

Application filed October 25, 1898. Serial No. 694,556. Term of patent 7 years.

To all whom it may concern:

Be it known that I, WILLIAM NESS, Jr., a citizen of the United States, residing at Spring Forge, in the county of York and State of Pennsylvania, have invented and produced a Design for Harness-Tugs, of which the following is a specification.

My invention relates to designs for harness-tugs illustrated in the accompanying drawings, in which—

Figure 1 is a perspective view of a harness-tug embodying my invention, and Fig. 2 is a vertical longitudinal section thereof.

My design comprises the unitary article shown in the drawings; and it consists of a back wall A and an outer curved wall B, forming between them the opening C. The wall A has its ends projecting beyond the wall B, as

shown at b and c, and the projection c is provided with a transverse horizontally-extending opening d. Formed in the back wall A, at the lower end of the opening C, is a vertically-arranged elongated opening e.

Having thus described my invention, what I claim, and desire to secure by Letters Patent, is—

The design for a harness-tug substantially as herein shown and described.

In testimony whereof I have hereunto set my hand in the presence of two subscribing witnesses.

WILLIAM NESS, JR.
